UNITED STATES PATENT OFFICE.

CLOYDE B. EATINGER, OF CARROLL, IOWA.

HEATING SYSTEM.

Application filed October 2, 1925. Serial No. 60,084.

My present invention has reference to a heating system for automobiles.

My object is the provision of a device of this character whereby heat from the engine 5 may be directed to radiators arranged beneath or adjacent to the seats of the automobile, and wherein such heat may be shut off when not desired.

A further object is the construction of an 10 exhaust manifold for automobile engines, having a swingable valve therein dividing the same into two compartments, through one of which the heated exhaust gases from the engine are directed to the muffler in the 15 usual manner, and the other having a coil arranged therein which has pipe connections with radiators in the automobile, said coil and radiators being filled with water, the said water being heated when the swingable 20 valve is swung to direct the full force of the heated exhaust gases from the engine against the coil.

The drawings illustrate a satisfactory embodiment of the improvement.

25 In the drawings:—

Figure 1 is a side elevation of an automobile equipped with my heating system, parts being in section.

Figure 2 is an enlarged sectional view on 30 the line 2—2 of Figure 1.

Figure 3 is a sectional view on the line 3—3 of Figure 1.

Referring now to the drawings in detail, the numeral 1 designates broadly an ordinary 35 construction of automobiles and 2 the motor thereof.

In carrying out my invention I make use of a specially constructed manifold for the motor 2. This manifold is indicated by the 40 numeral 3 and is of a greater width than that ordinarily employed but is connected to the engine in the same manner as the ordinary exhaust manifold. The manifold has an outlet 4 which is piped in the usual manner to 45 the muffler for the engine. The manifold has its ends, adjacent to its top, provided with lugs 5 that receive therebetween the notched upper edges of a plate 6. In the bottom of the manifold there is a stop 7 for 50 contacting engagement with the plate 6. The plate has secured in its upper edge a shaft 8 that finds bearings in the lugs 5. The shaft 8 is, of course, secured to the plate. The plate is in the nature of a valve as well

as a division plate for dividing the manifold 55 into an inner compartment 9 and an outer compartment 10. The shaft 8 has its outer end connected, preferably through the medium of a flexible joint 11, to an operating rod 12 having an offset handle end 13. The 60 rod 12 passes through the dash of the automobile and the handle 13 thereof is designed to be engaged by suitable means for holding the said handle at desired positions. By virtue of such means the division or valve plate 65 6 may be retained to close the compartments 9 and 10 or may be retained when swung to an upward position as disclosed by the dotted lines in Figure 3 to establish a communication between the compartments. 70

In the compartment 10 there is a coil 14. This coil has its opposite ends connected with pipes or tubes 15 and 16, respectively. The tube or pipe 15 communicates with pipes 17, leading to the inlets of radiators 18 and 19 which are disposed adjacent to the seats of the automobile, while the pipe 16 is connected to the outlets for the said radiators. In the pipe 16 there is a drain cock 20 and in the pipe 15 there is a filler spout 21. The water inlet to the radiator is controlled by a valve 22. 75

In warm weather the exhaust gases from the engine pass directly through the compartment 9 and through the muffler. The 80 valve plate 6 is then, of course, in vertical or closed position. During winter driving the valve 6 is raised to establish a communication between the compartments so that the heater coil 14 will be subject to the direct 85 force of the heated gases from the engine. In this manner the coils soon become heated, the water through the system is continuously circulated so that the radiators are 90 likewise easily and quickly heated. 95

Having described the invention, I claim:—

A manifold for internal combustion engines, comprising a comparatively wide member, a longitudinally extending swingable valve therein dividing the member into two compartments, one of said compartments communicating with an engine and having an exhaust, a heater coil in the second compartment and having its ends extending therethrough, and designed to be connected 100 to a radiator or the like. 105

In testimony whereof I affix my signature.
CLOYDE B. EATINGER.
